Attorney

UNITED STATES PATENT OFFICE.

THEOPHILUS T. BURCHELL, OF MANCHESTER, KENTUCKY.

SECRET DRAWER.

1,247,367.

Specification of Letters Patent. Patented Nov. 20, 1917.

Application filed September 19, 1916. Serial No. 120,986.

To all whom it may concern:

Be it known that I, THEOPHILUS T. BURCHELL, a citizen of the United States, and resident of Manchester, in the county of 5 Clay and State of Kentucky, have invented certain new and useful Improvements in Secret Drawers, of which the following is a specification.

This invention has reference generally to 10 improvements in furniture, and more particularly relates to a secret drawer especially adapted for use in connection with a table.

The invention has for its primary aim and 15 object to provide novel means for mounting a drawer on an article of furniture such as a table in order that the contents thereof may be preserved with secrecy and safety, improved means being associated therewith and positioned so as to be known only to 20 one of authority for releasably holding the drawer in a closed position.

It is also contemplated by this invention to provide improved locking means for the 25 drawer, said means being operable by a key and positioned so as not to be easily disclosed to one unfamiliar therewith.

More particularly, the present invention 30 embraces the provision of novel means whereby the drawer may be attached to any table or other article of furniture.

Among the other aims and objects of the 35 invention may be recited the provision of a device of the character mentioned with a view to compactness, the number of parts of which are few, the construction simple, the cost of production low and the efficiency high.

Other improvements and novel details in 40 the construction and arrangement of the various parts of the device will be brought out more in detail in the description to follow, which, for a clear understanding of the invention, should be considered in connection with the accompanying drawings, forming 45 a part hereof, and wherein is disclosed, for the purpose of illustration, convenient and satisfactory embodiments of the invention. It is to be noted, in this connection, that minor changes in the construction and arrangement of the parts may be made without departing from the spirit of the invention or the principle of operation of the various parts.

The invention is clearly illustrated in the 50 accompanying drawings, in which:

Figure 1 is a side elevation, partly in sec-

tion, showing my invention in a closed position.

Fig. 2 is a side elevation of my invention in an open position. 60

Fig. 3 is a perspective of a modified form of a means for attaching the drawer in position.

Similar characters of reference are employed in all of the above described views, 65 to indicate corresponding parts.

Referring now, more particularly, to the accompanying drawings I provide a table indicated generally by the numeral 1, and it is to be understood at the outset that it is 70 only illustrated in order that a thorough comprehensive understanding of the invention may be obtained, as the table itself forms no important part of the invention, since the invention can be readily associated 75 with other articles of furniture. The table as illustrated consists of a top 2, and a side

piece 3, extending along the under surface of the top adjacent the side edge. The rest of the table may be of any conventional 80 construction. Mounted for pivotal and sliding movement on the under surface of the top 2, are supports 4, which may be and preferably are constructed of strips of relatively flat metal having longitudinal slots 5, 85 adjacent one end thereof. The supports are preferably connected to suitable fastening devices 6, carried in ears 7, which are in turn connected to the under surface of the top, the fastening devices 6, being operably arranged in the slots 5. These supports 4, are 90 preferably four in number and have their lower ends pivoted through the medium of suitable fastening devices 8, to the respective 95 sides of a drawer 9, of a conventional construction. An operating knob 10, is connected to the under surface of the bottom of the drawer 9, and it will be readily apparent that when the same is pushed inwardly the supports will slide inwardly through the medium of the slots and fastening devices and when the fastening devices are arranged at the outer ends of the slots, because of the 100 weight of the drawer 9, the supports will pivot about the fastening devices 6 and consequently maintain the drawer in a suspended or open position in spaced relation with the surface of the top 2, as illustrated in 105 Fig. 2.

For the purpose of releasably retaining the drawer in a closed position in abutting relation with the under surface of the top 110

of the table, I have provided a pawl 11, pivotally mounted by means of a suitable pin 12, in a recess 13, in the under surface of the top 2. The engaging end 14, of the pawl extends at an angle from the main portion and is removably arranged in a notch 15, in the upper edge of one side of the drawer 9 so as to prevent inward sliding movement of the drawer. A spring 16, has its respective ends bearing against the bottom of the recess and the engaging end of the pawl, and serves to normally hold the pawl in yielding engagement with the notch, while the outer end of the pawl terminates in a finger piece 17, which is normally arranged in a corresponding opening 18, in the top 2 and communicated with the recess 13, so as to consequently allow the finger piece to lie flush with the top 2 as shown in Fig. 1.

20 In order to removably lock the drawer in a closed position, I have arranged a lock casing 19, in a corresponding recess 20, in the inner surface of the side piece 3, the locking members 21, being arranged to releasably engage a keeper 22, in the front end of the drawer which abuts the side piece 3. An operating key 23, is arranged to releasably engage the lock casing to consequently actuate the locking members 21.

30 It is, of course, to be understood that I am not limited to the particular form of lock shown as another type may be used to good advantage. However, it is desirable that the casing be mounted as shown so as not to be easily disclosed to the view of one unfamiliar therewith, thus preserving the secrecy of the drawer to a great extent.

In Fig. 3 of the drawings, I have shown another form of means for attaching the supports to the under surface of the table. In the present instance this means consists of a supporting bar 24, which may be and preferably is constructed of a strip of relatively flat metal securable by means of suitable fastening devices (not shown) adapted to pass through suitable spaced opening 25. Spaced ears 26, are struck out from one edge of the bar 24, and depend from the main portion thereof as shown in Fig. 3.

50 There are, of course, two of these supporting bars required when this form of attaching means is employed, being securable in spaced relation on the under surface of the top so as to consequently be arranged upon opposite sides of the drawer as is obvious.

The mode of operation of the invention may be reviewed as follows:

Assuming that the drawer is in a position shown in Fig. 1 and it is desired to open the same the key 23, is operated to release

the locking members 21 whereupon the finger piece 17 is depressed by the finger of one hand, (not shown) and the knob 10 is engaged by the other hand, (not shown) and pushed inwardly in order that the supports 65 will slide about the fastening devices 6 because of the slots 5. When the outer ends of the slot strike the fastening devices, on account of the weight of the drawer 9 the latter will swing the supports about the fastening devices 6, to allow the drawer to be suspended in an open position in spaced relation to the top 2 of the table as indicated in Fig. 2 of the drawings. In closing the drawer, it is only necessary to push it inwardly and upwardly until it strikes the under surface of the top 2 whereupon it is drawn forwardly until it strikes the side piece 3, allowing the pawl to automatically engage the notch 15 and thus automatically 70 lock the drawer in a closed position.

As many changes could be made in the above construction and many apparently different embodiments of this invention could be made without departing from the 85 scope thereof, and it is intended that all matters contained in the above description or shown in the accompanying drawings shall be interpreted as illustrative and not in a limiting sense. It is also to be understood 90 that the language used in the following claim is intended to cover all of the generic and specific features of the invention herein described and all statements of the scope of the invention, which, as a matter of language, might be said to fall therebetween.

Having thus fully described my invention, what I claim as new and desire to secure by Letters Patent, is:

A device of the character described including in combination with the top of a table, a drawer, slotted supports having their slotted ends slidably and pivotally connected to the under surface of the table top, a drawer pivotally connected to the outer ends of the supports, and having one edge provided with a notch, a pawl pivotally mounted in the under surface of the top of the table and yieldingly engageable with the recess in the notch, a finger piece formed on the inner end of the pawl and operable from the upper surface of the top to release the pawl to consequently allow the supports to be moved to suspend the drawer, and means for locking the drawer when in a 115 closed position.

In testimony whereof, I affix my signature hereto.

THEOPHILUS T. BURCHELL.

Copies of this patent may be obtained for five cents each, by addressing the "Commissioner of Patents, Washington, D. C."
